ELEVATOR CONTROL SYSTEM

Edgar M. Bouton and Harold W. Williams, Chicago, Ill., assignors to Westinghouse Electric Elevator Company, Chicago, Ill., a corporation of Illinois

Application July 11, 1936, Serial No. 90,095

16 Claims. (Cl. 172—152)

Our invention relates to elevator control systems and more particularly to systems for controlling the operation of the elevator motors in making one floor runs and in making runs of more than one floor as well as effecting landings at the floors.

In the operation of elevator systems in which the cars are run at various speeds and particularly in two-speed systems in which the cars may be operated at a normal low speed or a normal high speed, it is difficult to provide an automatic control system which will automatically decelerate the car from its high speed to a stop at a floor when the car has been making a run of more than one floor, and to also cause the same car, in making a one floor run, to accelerate to its highest speed for a one floor run and then automatically decelerate to the stop at the next floor. It is not practical to make a one floor run on "low speed" because too much time would be consumed in making the run. On the other hand, it is not practical, in a one floor run, to get the car up to its highest speed, because the car could not reach such high speed and yet be decelerated at an agreeable rate of deceleration to stop at the next floor. That is, the car cannot be accelerated to its normal "high speed" and then be decelerated to its landing speed within the confines of a one floor run.

Therefore, the object of our invention is to provide a system in which a one floor run may be automatically accomplished in the shortest possible time consistent with agreeable acceleration and agreeable deceleration.

It is also an object of the invention to provide an elevator control system which will automatically select and follow through the acceleration and deceleration necessary for a one floor run, or the acceleration and deceleration for a run of more than one floor, without requiring any attention to such operation by the car attendant; that is, to provide a system in which the car attendant will throw his switch for starting and stopping the car and will thereby automatically cause the car to operate under the best running conditions whether the run is for one floor or for several floors.

It is also an object of our invention to provide an automatic decelerating and stopping system for elevators in which the car may be "inched" into an accurate landing position at a floor if for some reason the automatic landing system causes the car to stop either a few inches short of or a few inches beyond the exact point

at which it should stop to take on or let off passengers.

For a better understanding of our invention, reference may be had to the accompanying drawings, in which

Figure 1 is a representation of an elevator car disposed for operation past several floors in a hatchway (not shown).

Fig. 2 is a diagrammatic representation of a control system for operating the car shown in Fig. 1, and

Fig. 2A is a diagrammatic representation of the relays embodied in the control system shown in Fig. 2.

The diagram shown in Fig. 2 is drawn in what is known as the straight line style for electric circuits. The illustration of the relays in Fig. 2A shows them with their coils and contact members disposed in horizontal alignment with their positions in the straight line circuits of Fig. 2 so that the reader may readily determine the identity of any relay, the number and kind of its contact members and the position of its coil and its contact members in the straight line circuit.

Referring more particularly to the drawings, we have illustrated an elevator car A disposed for operation past the 8th, 9th and 10th floors in an elevator shaft indicated by the dotted line 7. Obviously, the car may serve any desired number of floors and it may be suspended by a suitable cable 11 which passes over an operating drum 12 to a counterweight 13.

The drum 12 for operating the car is driven by a low-speed motor 14 and a high-speed motor 15. The motors are mounted on a suitable shaft 16 connected to the elevator drum 12 through a suitable reducing gear drive 17 so that the motors may operate at somewhat higher speed than the speed at which it is necessary to drive the car. A suitable electromagnetic brake 18 is provided for stopping the car and holding it in position when the motors are deenergized.

The low-speed motor 14 comprises a rotor 20 and a stator 21, while the high-speed motor 15 comprises a rotor 22 and a stator 23. The stators of the motors are provided with impedance means shown as a plurality of resistors r1 to r12 to assist in controlling the acceleration and deceleration action of the motors.

The motors may be connected to any suitable source of supply represented by the conductors L1, L2 and L3, through a main line switch 24.

The control system for the motors is shown as supplied with low-voltage energy from a pair of supply conductors L+ and L-, connected to

the main supply circuit through a plurality of rectifiers 25. The rectifiers may be of any satisfactory design, but preferably of the copper oxide type.

5 The relays, etc. in the system are listed as follows:

- U=Up direction switch.
- D=Down direction switch.
- E=Low speed switch.
- 10 F=Low speed accelerating relay.
- G=Low speed accelerating relay.
- M=Time relay for low speed accelerating relay F.
- N=Time relay for low speed accelerating relay G.
- P=High speed relay.
- Q=Interlocking relay for high speed.
- R=High speed switch.
- 20 S=High speed accelerating relay.
- T=High speed accelerating relay.
- V=Inductor energizing relay.
- W=Slow down inductor relay.
- X=Stopping inductor relay.
- 25 Y=Relay for selecting deceleration point or plate.
- CS=Control switch in car.

The motors may be controlled to start and stop the car through the use of a manually operated switch or controller CS mounted in the car. The car switch is provided with two accelerating points, (a low-speed and a high-speed) for the up direction and two accelerating points, (a low-speed and a high-speed) for the down direction. 30 In starting the car, the switch CS controls an up direction switch U and a down direction switch D which prepare the motor circuits for connection to the main line conductors L1, L2 and L3. When the up direction switch U is energized, the 35 motors are prepared for operating the car in the up direction. When the down direction switch D is energized, the motors are prepared for operating the car in the down direction.

In addition to the direction switches, a low-speed switch E, controlled by either the up direction switch U or the down direction switch D is provided for connecting the low speed motor 14 for operation.

A first low-speed accelerating relay F and a 50 second low-speed accelerating relay G are provided for controlling the connection of the resistors r1 to r12 in the circuit of the stator 21 of the motor 14.

A first time delay relay M and a second time 55 delay relay N are provided for controlling the low-speed accelerating relays F and G.

A high-speed relay P is provided for effecting control of the motors to operate the car at high speed. This high-speed relay is responsive to 60 movements to the second or high speed points on the car switch and it has associated with it a self-holding interlocking relay Q to insure acceleration and deceleration of the motors in correct order.

65 A high-speed switch R is disposed to be controlled by the high-speed relay P for connecting and disconnecting the high-speed motor 15 to the supply conductors L1, L2 and L3. Associated with the high-speed switch R, is a pair of high-speed accelerating relays S and T for connecting and disconnecting the accelerating resistors r1 to r6 in the circuit of the stator of the motor 15. The relays S and T are provided with dash pots to delay their closing for predetermined periods 75 so as to ensure the connection and disconnection

of the resistors after the expiration of the correct time intervals.

The circuit of the brake 18 includes contact members operated by the low speed switch E and the high speed switch R so that the brake will be released when either motor is energized to move the car. In accordance with our invention, we have provided a novel arrangement for securing a better operation of the control system than heretofore provided. This arrangement includes not only means for delaying the operation of the time relays M and N but also a means for so connecting the interlocking relay Q with the time relays M and N that it will control the timing of these relays to effect a rapid disconnection and connection of the resistors r1 to r12 with the low speed motor when the car is being "inched" into a floor and to effect a slow disconnection of these resistors with the low speed motor when the car is being decelerated from a high speed run. 15

The car may be started in operation by moving the car switch to the right or left in accordance with the direction desired, and it may be stopped by centering the car switch; that is, by returning the switch to its "off" position. Any suitable landing system may be employed for automatically stopping the car level with the floors it serves in response to the centering of the car switch. As one example of such a landing system, we have illustrated an automatic inductor relay 20 landing system similar to that disclosed in Patent 1,884,446, issued October 25, 1932, to K. M. White and G. H. Hearn, and assigned to the Westinghouse Electric Elevator Company. This landing system responds to the centering of the car switch by automatically decelerating and stopping the car accurately level with the floor at the next floor landing. The landing system includes a high-speed decelerating device or inductor relay W and a stopping inductor relay X for 25 causing the car to be automatically decelerated from its high speed and brought to a stop at the floor at which it is to be stopped. The inductor relay W is mounted on the car in position to operate with a decelerating device or inductor plate 9DWL or 9DWS for the down direction at the 9th floor. The stopping inductor relay X cooperates with an inductor plate 9DX for the down direction at the 9th floor. The inductor plates are constructed of magnetic material and are mounted in the hatchway in such position as to cooperate with and open the contact members of the inductor relays on the car when the relays are in an energized condition as the car approaches a stop at a landing. 30

For simplicity only the down inductor plates at the 8th and 9th floors are shown in Fig. 1, but it will be understood that a similar set of down plates and a similar set of up plates may be provided for each floor served by the car intermediate its upper terminal landing and its lower terminal landing (not shown). The car may be stopped at its terminals by the usual limit switches LS. The down inductor plates at the 9th floor are marked as plates 9DWL and 9DWS 35 for deceleration and as plate 9DX for stopping. 40

As shown, each inductor relay is provided with two sets of contact members. For a down stop at the 9th floor, the contact members DWL of relay W cooperate with either the inductor plate 9DWL or the plate 9DWS in starting deceleration to landing speed and the down contact members 45 9DX of the stopping relay X cooperate with the down stopping plate 9DX in stopping the car after it is decelerated to its landing speed. This 50

deceleration and stopping is effected because the contact members of the inductor relays are so connected with the car control circuits that, when the inductor relays are energized as the car passes the plates, the opening of the contact members effects the deceleration and stopping of the car. For the up direction, the contact members $UW1$ of relay W and the contact members $UX1$ of the relay X cooperate with up inductor plates (not shown) similar to those for the down direction.

The inductor relays are of the self-holding type, that is, when they are energized but have not yet come opposite an inductor plate, the contact members remain closed, but when the relay comes opposite an inductor plate, the contact members adjacent that plate move to their open position and are held in such open position until the inductor relay is deenergized. However, if desirable, any other suitable type of inductor relays may be utilized.

The exact position of the inductor plates in the hatchway and of the inductor relays on the cars cannot be here given because such positions vary in each installation by reason of difference in hoisting motors, weight of cars, height of ceilings, etc. However, elevator mechanics have found little difficulty in installing the plates and inductor relays correctly when the cars are first tried out in operation, so that the car will be stopped level with the next floor to which it can be agreeably decelerated and stopped after centering of the car switch.

The elevator system illustrated in connection with this invention is of the type often utilized for operating cars at a speed of from 200 to 250 feet per minute. In operating cars of this character having a normal low speed motor and a normal high speed motor, we provide, in accordance with our invention, for automatically starting deceleration at one distance ahead of the floor stop after a run of two or more floors and for starting deceleration at a shorter distance from the floor stop in making only a one-floor run. In making a one-floor run, this permits the car to be accelerated to the highest speed from which it can be agreeably decelerated and stopped at the next floor.

To carry out these features of the invention, the two decelerating plates for each direction at each floor are positioned to start deceleration at different points and a selecting relay Y is provided to automatically respond to the operation of the car control system so as to cause the decelerating inductor relay to be operated by the first plate $9DWL$ when stopping after a long run and by the plate $9DWS$ when stopping in a one-floor run. The high speed inductor plate $9DWL$ for the 9th floor is disposed to initiate deceleration of the car for a down stop at the 9th floor when landing from a run of two or more floors. The high speed decelerating plate $9DWS$ is mounted at a shorter distance from the 9th floor, so that a down car can accelerate from a stop at the 10th floor to the highest speed from which it can be safely decelerated and stopped at the 9th floor and can then be safely decelerated by the plate $9DWS$ to landing speed for the 9th floor.

It is believed that the invention may be understood best by an assumed operation.

It will be assumed that the car A is standing above the 10th floor, say, at the 12th or 13th floor, and that the main line switch 24 is closed to prepare the car for operation. In this condition, the inductor energizing relay V is energized

but does not affect the system, as the car is standing still. The car will be operated to run down to and stop at the 9th floor, thereby making more than a one-floor run. In starting the car the attendant moves the car switch in its counter-clockwise direction to full-on or high speed position for the down direction. As the switch engages its low speed position or first contact point 30 , it energizes the down direction switch, to effect down operation of the car by the circuit: from $L+$ through $CS-30$, $LS2$, D , 31 , to $L-$.

The energized switch D closes its contact members $D1$ and $D2$, thereby preparing a down circuit for the motors 14 and 15 and closes its contact members $D5$, thereby energizing the selecting relay Y , the time delay relay M , the time delay relay N and the low speed switch E for starting the motor 14 and controlling its acceleration to its normal speed.

The circuit for relay Y extends from $L+$ through $D5$, $Q2$, Y , 33 to $L-$. The circuit for relay M extends from $L+$ through $D5$, $E4$, M , 33 , to $L-$. The circuit for relay N extends from $L+$ through $D5$, $F3$, N , 33 to $L-$. The circuit for relay E extends from $L+$ through $D5$, E , $R6$, 33 to $L-$.

The closing of the contact members $E3$ of relay E energizes the brake coil 18 by a circuit from $L1$, through $24a$, $D2$, $E3$, 18 , $D1$, $24b$ to $L2$ to release the brake from the shaft 16 . The closing of the contact members $E1$ and $E2$ of relay E completes the circuit for the motor 14 to start it in operation. This motor circuit extends from $L1$ through $24a$, $D2$, $21a$, $r7$, $r10$ to center junction 40 ; from $L2$ through $24b$, $D1$, $E2$, $21b$, $r8$, $r11$ to 40 ; from $L3$ through $24c$, $E1$, $21c$, $r9$, $r12$ to 40 . The release of the brake and the energization of the motor 14 causes the car to be started on its down trip.

The opening of the contact members $E4$ of the relay E deenergizes the relay M but that relay does not open yet because of its time delay resistor $r14$.

Referring again to the operation of the car switch, the fact that it was moved immediately to its full-on or high-speed position at the start caused the high speed motor 15 to be energized right away after the energization of the motor 14 . In fact, the energization of the motor 15 and the deenergization of the motor 14 follow so closely that the resistors in the circuit of the motor 14 are not short circuited to exclude them before the motor 14 is cut out of operation and the motor 15 is put into operation. This is accomplished by the switch CS closing its contact members 32 , thereby energizing the high speed relay P to effect the starting of the motor 15 , the cutting out of the motor 14 and the acceleration of the motor 15 to its normal high speed. The circuit for relay P extends from $L+$ through $CS-32$, $LS4$, P to $L-$.

The energized relay P closes its contact members $P3$, thereby energizing the interlocking high speed relay Q by a circuit from $L+$ through $D5$, Q , $Y2$, $P3$, 33 to $L-$. The energized relay Q immediately opens its contact members $Q2$, thereby deenergizing the selecting relay Y . However, the relay Y is provided with a timing element or resistor $r13$ so that it remains in its operated position for a predetermined time, but, inasmuch as the car is now operating on a long run, the final opening of the relay Y can not affect the operation of the car and when it is to be stopped it

will start its deceleration for a stop from a long run.

The closing of the contact members **Q3** and **Q4** connects the resistors **r15** and **r17** in the time delay circuits of the relays **M** and **N** to control the delay period of those relays when the car is being decelerated to a stop, as will be described later.

The closing of the contact members **P2** of the energized relay **P** energizes the high speed switch **R** for stopping the low speed motor **14** and for putting the motor **15** into operation and accelerating it to its normal high speed. This circuit extends from **L+** through **34**, **R**, **P2** to **L-**.

The closing of the contact members **R1** and **R2** of the energized relay **R** completes a circuit for energizing the windings **23** of the high speed motor **15** for the down direction, and it now operates to run the car in the down direction. This motor circuit extends from **L1** through **24a**, **D2**, **23a**, **r1**, **r4**, to junction **41**; from **L2** through **24b**, **D1**, **R2**, **23b**, **r2**, **r5** to **41**; from **L3** through **24c**, **R1**, **23c**, **r3**, **r6** to **41**.

The opening of the contact members **R6** of relay **R** deenergizes the low speed relay **E** which closes its contact members **E4** to again energize relay **M** and prevent acceleration of motor **14** and opens its contact members **E1** and **E2**, thereby deenergizing the motor **14** so that it ceases to affect the operation of the car. Both the motor **14** and the motor **15** will be in an energized condition momentarily when the relays operate to change from the low speed motor to the high speed motor and this will tend to provide a smooth transition from low speed operation to high speed operation of the car.

The closing of the contact members **R7** of the relay **R** energizes the high speed accelerating relay **S** by a circuit from **L+** through **34**, **S**, **R7**, **P2** to **L-**. This relay is provided with a dashpot **36** for delaying its closing for a predetermined time. After the expiration of that predetermined time, the relay **S** closes, thereby closing its contact members **S1** and **S2**, thus short-circuiting the resistors **r4**, **r5** and **r6** from the field circuit of the motor **15**. This increases the torque of the motor which results in increasing its speed. As the same time, the operating relay **S** closes its contact members **S3**, thereby energizing the high speed accelerating relay **T**. This relay **T** is also provided with a dashpot **37** which prevents it from closing for a predetermined time after it is energized. Upon the expiration of this predetermined time, the relay **T** closes its contact members **T1** and **T2**, thereby short-circuiting the resistors **r1**, **r2** and **r3** in the field of the motor **15**, thus increasing the torque of the motor which results in still further increasing its speed. The motor **15** now moves the car downwardly at normal high speed.

It will be assumed now that the car is moving down the shaft and that, as it passes the 9th floor, the attendant centers the car switch **CS** for a stop at the 8th floor. The centering of the car switch will cause the car to automatically decelerate and stop level with the 8th floor, by energizing the inductor energizing relay **V**. The circuit for relay **V** extends from **L+** through **CS-42**, **V** to **L-**.

The energized relay **V** closes its contact members **V1** thereby energizing the high speed inductor relay **W** by a circuit extending from **L+** through **D5**, **V1**, **Y1**, **W**, **33** to **L-**. The relay **W** is energized immediately by the action of the

relay **V** because it is a long run and the contact members **Y1** have been closed by the timing out of the selecting relay **Y**. Therefore, the relay **W** will be operated by the long run plate **8DWL** instead of the one-floor run plate **8DWS**. As the car continues downwardly, the energized relay **W** comes opposite the long run inductor plate **8DWL** and is thereby operated to open its contact members **DW1**. The opening of the contact members **DW1** deenergizes the high speed relay **P** to effect deceleration of the car from its normal high speed to its landing speed. The deenergized relay **P** closes its contact members **P1** thereby energizing the low speed switch **E** by the circuit previously described. The energized switch **E** closes its contact members **E1** and **E2** thereby re-energizing the windings **21** of the low speed motor **14** to start that motor in operation, in the transfer of the car from operating by the high speed motor to operation by the low speed motor.

The opening of the contact members **E5** in the circuit of the high speed switch **R** deenergizes that switch thereby causing it to open its contact members **R1** and **R2** thus deenergizing the windings **23** of the high speed motor **15**. This cutting out of the motor **15** and cutting in of the motor **14** causes the car to decelerate.

The energized low speed switch **E** also opens its contact members **E4** thereby deenergizing the time relay **M**. After the expiration of a predetermined period, the deenergized relay **M** closes its contact members **M1** thereby energizing the low speed accelerating relay **F** by a circuit from **L+** through **D5**, **M1**, **F**, **E6**, **33** to **L-**. The energized relay **F** closes its contact members **F1** and **F2** thereby short circuiting the resistors **r10**, **r11**, and **r12** in a winding **21** of the motor **14**, thus increasing the retarding torque of the motor.

It should be noted that the time delay in the deenergizing of the relay **M** in this particular instance is increased by reason of the fact that the contact members **Q3** are closed in the circuit of the resistor **r15**. This provides a parallel path through the resistor **r14** and **r15** thereby giving a lower resistance and increasing the time delay of the relay **M**.

The energized relay **F** also opens its contact members **F3** in the circuit of the energized relay **N**. By reason of the fact that the relay **N** is provided with time delay resistors **r16** and **r17** and the fact that the contact members **Q4** in the circuit of the resistor **R17** are closed, the time delay of the relay **N** is also increased. The relay **N** is fully deenergized and closes its contact members **N1** thereby energizing the accelerating relay **G** by a circuit from **L+** through **D5**, **N1**, **G**, **E6**, **33** to **L-**. The energized relay **G** closes its contact members **G1** and **G2** thereby short circuiting the resistors **r7**, **r8**, and **r9** in the motor **14**, thus further increasing the retarding torque of the motor. The increased torque of the low speed motor effects a further deceleration of the car from the high speed at which it was operated by the high speed motor until it comes down to its normal landing speed.

The closing of the contact members **R5** energizes the stopping inductor relay **X** to effect the stopping of the car when it gets to the 8th floor. This circuit extends from **L+** through **D5**, **V1**, **Y1**, **R5**, **X**, **33** to **L-**. As the car, now operating at landing speed, approaches closely to the 8th floor, the energized inductor relay **X** comes opposite the stopping inductor plate **8DX** and is

thereby operated to open its contact members DX1 to effect the stopping of the car level with the floor. The opening of the contact members DX1 in the circuit of the down direction switch 5 D, deenergizes that switch to stop the car level with the 8th floor. The opening of the contact members D1 and D2 deenergizes the motor 14. The opening of the contact members D5 deenergizes the low speed switch E which opens its 10 contact members E3 thereby deenergizing the brake 18 and applying it to stop and hold the car at the 8th floor. The opening of the contact members D5 also deenergizes the interlocking high speed relay Q, the high speed inductor 15 relay W and the stopping inductor relay X.

By reason of the foregoing operation of the car over a long run, it is seen how it responds to the movement of the car switch in accelerating to high speed, how the decelerating inductor 20 relay is energized before the car reaches the long run inductor plate by the centering of the car switch, how the high speed motor is cut out and the low speed motor cut in in decelerating the car, how the resistors in the winding of the low 25 speed motor 14 are brought in slowly by the time delay relays M and N to still further decelerate the car and how the car is finally stopped level with the 8th floor.

It will be assumed now that the car has been 30 operated for some time and is at present standing at the 9th floor on a down trip. It will also be assumed that the car attendant, knowing that the car is to be stopped at the 8th floor, moves the car switch in its counterclockwise direction 35 to full on position and then recenters it to make a one floor run and stop at the 8th floor. This operation will show how the selecting relay Y operates to cause the decelerating relay W to fail to operate on the long run plate 8DWL and 40 to operate on the short run plate 8DWS, when making a one floor run.

The movement of the car switch to its full on position energizes the down direction relay D and the high speed relay P to energize the time 45 relay M, the time relay N, the selecting relay Y, the slow speed switch E, the interlocking relay Q and the high speed switch R to accelerate the car toward its high speed as described in connection with the long run previously indicated. 50 However, inasmuch as the car switch CS has been re-centered, the inductor energizing relay V has been energized as previously described. This closes the contact members V1 in the circuit for the high speed inductor relay W. However, 55 the selecting relay Y, although it has been deenergized by the opening of the contact members Q2, has not yet been deenergized, because of the time delay caused by its resistor r13. Therefore, its contact members Y1 are still open, and 60 although the relay V has been energized, it cannot yet energize the relay W because of these open contact members. However, selecting relay Y times out within a few seconds and then its contact members Y1 close. By this time, the car, 65 upon leaving the 9th floor, has passed the long run decelerating inductor plate 8DWL. The closing of the contact members Y1 of the relay Y and the already closed contact members V1 energize the inductor relay W after the car passes 70 the plate 8DWL but before it reaches the plate 8DWS. As the car continues toward the 8th floor, it passes the inductor plate 8DWS and the inductor relay W is thereby actuated to open its contact members DW1 thus deenergizing the high 75 speed relay P to effect deceleration of the car.

With the correct predetermined delay period for selecting relay Y and the position of the inductor plate 8DWS, deceleration of the motor 15 is started by the deenergization of the high speed relay P, before the time delay relay T has had 5 time to short circuit the resistors r1, r2 and r3 in the high speed motor 15. Therefore, although the car has reached a high speed, it has not quite reached the highest speed of which it is capable. However, in making a one-floor run, the highest 10 speed of which the car is capable is not desirable because that would require an uncomfortably rapid deceleration in order to stop at the next floor. Therefore, the relays are arranged to enable the car to reach the highest speed from 15 which it can, in making a one-floor run, be agreeably decelerated to a stop at the next floor. The deenergization of the high speed relay P effects the energization of the low speed switch E, the de-energization of the relays R, S and T, the ener- 20 gization of the stopping inductor relay X and the energization of the accelerating relays F and G to decelerate the car to its normal landing speed, in the same manner as previously de- 25 scribed in connection with the deceleration from the long run. Thus we have the same rate of deceleration as we had from the long run even though the car did not get up to as high a speed on its short run as it did on its long run.

In view of the assumed long run operation and 30 the assumed one-floor run operation, it will be seen how the selecting relay Y operates, by rea- 35 son of its deenergization soon after the car starts and its predetermined time delay, to automatically select and control the point at which decel- 40 eration begins in stopping from a long run stop and in stopping from a one-floor run, without any attention on the part of the car attendant beyond the necessity of centering his car switch within the proper time and that the car will, as 45 a result thereof, automatically decelerate and stop level with the next floor.

Occasionally, it will be found that the car, for 50 some reason, may fail to stop exactly level with the floor. In such cases, it is desirable for the 55 car attendant to be able to "inch" the car either up or down into its correct position. In practicing our invention, we have provided for securing a more rapid response of the low speed motor 14 while it is being operated in an "inching" oper- 60 ation than it had in the usual accelerating and decelerating operation. This is effected by caus- 65 ing the predetermined periods of delay in the re-closing of the accelerating relays M and N to be long when the car is operating on a long run or a one-floor run and to be short when the car is responding to an "inching" operation. In the foregoing assumed operations, it was shown how the time delay accelerating relays M and N were held open for a predetermined long period after 70 being deenergized, by the effect of the closed contact members Q3 and Q4 of the interlocking relay Q, during the normal runs of the car. The following assumed operation is now given to show how the contact members Q3 and Q4 remain open during an "inching" operation and thereby so affect the time relays M and N as to cause them to time out in a short period instead of a long 75 period.

It will be assumed now that the car failed to 70 land exactly level with the 8th floor and that, in fact, it landed a few inches above the 8th floor. Under these circumstances, the car attendant desires to "inch" the car down to the 8th floor and, therefore, moves the car switch CS from its 75

center position to its first down notch 30. Inasmuch as the switch CS is not moved to the notch 32 in this "inching" operation, the high speed relay is not operated and consequently the high speed interlocking relay Q is not energized. Therefore, the contact members Q3 and Q4 are open to shorten the time delay of the accelerating relays M and N. However, the movement of the switch to the contact member 30 energizes the 10 down direction switch D, by the circuit previously described, to effect movement of the car.

The energized switch D energizes the time delay relays M and N and the low speed switch E, as previously described in connection with the 15 operations of the car already given.

The energized low speed switch E energizes the low speed motor 14 and the brake 18. The release of the brake and the closing of the contact members E1 and E2 starts the motor in operation 20 and the car moves downwardly.

At the same time, the energization of the switch E opens its contact members E4 thereby deenergizing the time delay relay M. After the expiration of a predetermined short period, the relay M drops out thereby closing its contact members M1 and energizing the low speed accelerating relay F by the circuit previously described. The energized relay F closes its contact members F1 and F2 thereby short circuiting the resistors 30 r10, r11 and r12 in the circuit of the low speed motor 14 thus increasing its torque which causes it to accelerate rapidly.

The energized relay F also opens its contact members F3 thereby deenergizing the time delay relay N, which closes its contact members N1 after the expiration of a predetermined short period and thereby energizes the second low speed accelerating relay G, which closes its contact members G1 and G2 thereby short circuiting 40 the resistors r7, r8 and r9 in the winding of the motor 14. The elimination of these resistors increases the torque of the motor 14 which results in increasing its speed. As the car starts to "inch" toward the 8th floor, the car attendant 45 centers the car switch thereby opening its contact members 30 and deenergizing the down direction switch D and consequently the low speed switch E, the motor 14, the brake 18 and the accelerating relays F and G, which again stops the car, 50 this time level with the 8th floor.

In this connection, it should be noted that inasmuch as the interlocking relay Q was not energized during the "inching" operation, the contact members Q3 and Q4 in the circuits of the 55 resistors r15 and r17 were open, and, therefore, the time delay circuits for the relay M included only the resistor r14, and the time delay circuit for the relay N included only the resistor r16. This increased the resistance in the time delay 60 circuits of these relays and thereby caused them to cut out much quicker than when the car was accelerating or decelerating with the high speed locking relay energized while they were making a one or more floor run. It will be apparent that 65 this quick action of the accelerating relays is of benefit in "inching" into a level position with the floor because it causes the low speed motor to pick up quickly right at its start. However, it will also be apparent that such a quick action 70 on the part of accelerating relays when changing from the high speed motor to the low speed motor would not prove satisfactory and that it is much better, when decelerating from high speed, to cause the accelerating relays to operate slowly 75 so as to give the passengers an agreeable rate of

deceleration. Hence, it is seen that our novel provision of the interlocking relay Q and the time delay relays having different periods of timing out controlled by the relay Q have a decided advantage in operation. 5

It will also be seen that we have provided an elevator system in which the deceleration and acceleration in long run, one-floor run and "inching" operations is automatically controlled by the elevator system itself without the necessity of 10 special attention or special operation of any devices as the attendant on the car.

Although we have illustrated and described only one specific embodiment of our invention, we desire it to be understood that many changes 15 therein and many modifications thereof may be made without departing from the spirit and scope of the invention.

We claim as our invention:

1. In an elevator system for operating a car serving a plurality of floors, means for causing the car to start from a floor, means for causing the car to decelerate and stop at a floor, and a time delay device responsive to operation of the starting means for preventing operation of the decelerating means for a predetermined time after operation of the starting means. 20

2. In an elevator system for operating a car serving a plurality of floors, a car switch, means responsive to operation of the car switch to its 30 high speed position for causing the car to operate at a high speed, means responsive to movement of the car switch to its "off" position for decelerating and stopping the car at the next floor landing, and a selective device for controlling deceleration of the car to begin at one predetermined distance from the landing at which it is to be stopped when the car makes a one-floor run and for controlling the deceleration of the car to begin at another predetermined distance from the landing at which it is to be stopped when the car makes a run of more than one floor. 35

3. In an elevator system for operating a car serving a plurality of floors, a control system comprising a car switch, a high speed relay responsive to operation of the car switch for causing the car to operate at a high speed, means for causing deceleration and stopping of the car at a floor, means responsive to operation of the car switch and to operation of the high speed 45 relay for preventing operation of the decelerating means for a predetermined period after operation of the high speed relay. 50

4. In an elevator system for operating a car serving a plurality of floors, a controller means responsive to operation of the controller to an "on" position for starting the car in operation, means responsive to operation of the car switch to its "off" position for decelerating and stopping the car at the next floor for which it can be decelerated and stopped, a high speed relay responsive to operation of the controller to its high speed position for causing the car to operate at high speed, a selective device responsive to operation of the car switch to an "on" position in starting the car, and means responsive to operation of the high speed relay for causing the selective device to delay the operation of the decelerating means for a predetermined period of time. 60

5. In an elevator system for operating a car serving a plurality of floors, a car switch, means responsive to operation of the car switch in its "on" direction for starting and operating the car, means responsive to moving the car switch 70 75

- to its "off" position for decelerating and stopping the car at the next floor for which it can be decelerated and stopped, a selective device connected for operation by operation of the car switch to 5 an "on" position, a high speed relay responsive to operation of the car switch to its high speed "on" position for causing the car to operate at its high speed, a self-holding interlocking relay connected for operation by operation of the high speed relay, means responsive to operation of the interlocking relay for returning the selective device to its normal condition, means associated with the selective device for delaying for a predetermined time its return to normal condition, 10 and means responsive to the return of the selective device to its normal condition for rendering the decelerating means responsive to the next operation of the car switch to its "off" position.
6. In an elevator system for operating a car serving a plurality of floors, a car switch, a high speed relay responsive to operation of the car switch to its high speed position for causing the car to operate at high speed, means responsive to operation of the car switch from its high speed position to its "off" position for decelerating the car, said decelerating means comprising an inductor relay on the car and a long-run decelerating plate and a short-run decelerating plate associated with each floor for cooperation 15 with the inductor relay in decelerating the car for that floor, the long-run plate being disposed farther away from the floor than the short-run plate, a selective device connected for operation by operation of the car switch to an "on" position, an interlocking relay connected for operation in response to operation of the high-speed relay, means responsive to operation of the interlocking relay for returning the selective device to its normal condition, means associated 20 with the selective device for delaying for a predetermined time its return to normal condition, and means responsive to the return of the selective device to its normal condition for rendering the inductor relay responsive to the operation 25 of the car switch to its "off" position, whereby the inductor relay will be rendered effective for cooperation only with the long-run plate for the next floor to decelerate the car from a more-than-one-floor run and can be rendered effective 30 to cooperate only with the short-run plate for the next floor when making only a one-floor.
7. In an elevator system for operating a car serving a plurality of floors in a hatchway, control means, means responsive to operation of the control means for causing the car to run at high speed, means for decelerating the car, said decelerating means including a decelerating device on the car and a long-run cooperating device and a short-run cooperating device associated with each floor in the hatchway, and means responsive to a car-stopping operation of the control means in making a more-than-one-floor run for causing the decelerating device to be operated by the long-run cooperating device for 35 the floor at which a stop is to be made to decelerate the car and responsive to a car-stopping operation of the control means in making a one-floor run for preventing operation of the decelerating device by a long-run cooperating device and causing it to be operated by the short-run cooperating device for the floor at which the stop is to be made to decelerate the car, whereby deceleration of the car will be started in accordance with a long or a short run.
8. In an elevator system for operating a car 40 serving a plurality of floors in a hatchway, control means, means responsive to one operation of the control means for causing the car to run at high speed, means for decelerating the car, said decelerating means including an inductor relay on the car and a cooperating long-run plate and a cooperating short-run plate associated with each floor in the hatchway, and a selective device responsive to operation of the control means in making a more-than-one-floor run for causing the inductor relay to be operated to decelerate the car only by the long-run plate for the floor at which the stop is to be made and responsive to operation of the control means in 45 making a one-floor for preventing operation of the inductor relay by a long-run plate and causing it to be operated to decelerate the car by the short-run plate for the floor at which the stop is to be made, whereby deceleration of the car will be started in accordance with a long or a short run.
9. In a power system, an electric motive means, control means for effecting the starting and stopping of the motive means, means responsive to operation of the control means for 50 varying the torque of the motive means, and means responsive to predetermined degrees of operation of the control means for varying the rate at which the torque of the motive means is varied.
10. In a power system, a low speed electric motor and a high speed electric motor for operating a device, a control means for starting and stopping the motors, means responsive to a predetermined operation of the control means for 55 the "on" direction for energizing the low speed motor, means responsive to a continued operation of the control means for said "on" direction for deenergizing the low speed motor and energizing the high speed motor, means responsive to operation of the control means for varying the torque of the motors, and means responsive to the degree of operation of the control means for varying the rate at which the torque varying means effect variation in the 60 torque of the low speed motor.
11. In an elevator system for operating a car serving a plurality of floors, a low speed motor and a high speed motor for operating the car, a controller for controlling the energization of 65 the motors, impedance means connected with the low speed motor for varying its torque, means responsive to a predetermined operation of the controller for varying the amount of impedance at one rate, and means responsive to another predetermined operation of the controller for controlling the impedance varying means for operation at another rate.
12. In an elevator system for operating a car serving a plurality of floors, a low speed motor and a high speed motor for operating the car, a controller for controlling the energization of 70 the motors, a plurality of resistors disposed in the circuit of the low speed motor, means responsive to a predetermined operation of the controller for short circuiting part of the resistors upon the expiration of a predetermined time after the starting of the slow speed motor, and means responsive to another predetermined operation of the controller for changing the short circuiting means to short circuit said part of the resistors upon the expiration of a different predetermined time.
13. In an elevator system for operating a car serving a plurality of floors, a low speed motor 75

and a high speed motor for operating the car, a controller, for controlling the operation of the motors, means responsive to operation of the controller from its "off" position to its slow speed position for starting and to movement from said low speed position to said "off" position for stopping the slow speed motor, impedance for controlling the torque of said slow speed motor, means responsive to operation of the controller from said "off" position to said low speed position for varying the amount of said impedance for the slow speed motor after the expiration of a predetermined time, means responsive to operation of the controller from said low speed position to its high speed position for deenergizing said slow speed motor, for energizing said high speed motor, and for changing the impedance varying means to vary the amount of said impedance after the expiration of a different predetermined time when the slow speed motor is again energized.

14. In an elevator system for operating a car serving a plurality of floors, a low speed motor and a high speed motor for operating the car, a controller for controlling the energization of the motors, means responsive to operation of the controller from its "off" to its low speed position for energizing the low speed motor, and return of the controller to its "off" position without advancing beyond said low speed position for deenergizing the low speed motor, means responsive to operation of the controller from said low speed position to its "high speed" position for deenergizing the slow speed motor and energizing the high speed motor, means responsive to operation of the controller from said "high speed" position to its "off" position while the car is in operation for successively effecting deenergization of the high speed motor, reenergization of the low speed motor and subsequent deenergization of the low speed motor to stop the car, impedance means associated with the low speed motor, a time relay responsive to operation of the controller to its low speed position for controlling said impedance to vary the torque of the low speed motor, means for delaying operation of the time relay for a predetermined time, and means responsive to operation of the controller to its high speed position for causing the delaying means to delay operation of the time relay for a greater predetermined time than said first predetermined time when the slow speed motor is being energized during deceleration of the car from high speed.

15. In an elevator system for operating a car serving a plurality of floors, a low speed motor and a high speed motor for operating the car, a controller for controlling the energization of the motors, means responsive to operation of the controller from its "off" to its low speed position for energizing the low speed motor and to return of the controller to its "off" position without advancing beyond said low speed position for deenergizing the low speed motor, means respon-

sive to operation of the controller from said low speed position to its "high speed" position for deenergizing the low speed motor and energizing the high speed motor, means responsive to operation of the controller from said "high speed" position to its "off" position while the car is in operation for successively effecting deenergization of the high speed motor, reenergization of the low speed motor and subsequent deenergization of the low speed motor to stop the car, impedance means associated with the low speed motor, a first accelerating relay and a second accelerating relay for controlling the impedance, a time relay responsive to operation of the controller to its low speed position for controlling the first accelerating relay for varying a portion of the impedance to vary the torque of the low speed motor, a second time relay responsive to operation of said first accelerating relay for controlling said second relay for varying another portion of the impedance to additionally vary the torque of the low speed motor, means for delaying the operation of each of the time relays for a predetermined time, means responsive to operation of the controller to its high speed position for causing each of the delaying means to delay operation of its time relay for a greater predetermined time than said first predetermined time when the low speed motor is being energized during deceleration of the car from high speed.

16. In an elevator system for operating a car serving a plurality of floors, a low speed motor and a high speed motor, a controller, means responsive to operation of the controller to its low speed position for energizing the low speed motor, means responsive to operation of the controller to its "off" position for deenergizing the low speed motor to stop the car, means responsive to operation of the controller to its high speed position for causing the high speed motor to operate the car at high speed, means responsive to operation of the controller from its high speed position to its low speed position for decelerating and stopping the car at the next floor, a selective device responsive to operation of the controller from its "off" position to its low speed position, means responsive to operation of the controller to its high speed position for causing the selective device to prevent operation of the decelerating means for a predetermined time after the controller is operated to its high speed position, impedance means connected with the low speed motor for varying its torque, means responsive to operation of the controller to its low speed position for varying the impedance at one rate, and means responsive to operation of the controller to its high speed position for controlling the impedance varying means to operate at a rate different from said first named rate when the low speed motor is next energized in deceleration of the car from high speed.
